UNITED STATES PATENT OFFICE.

HOWARD PARKER, OF BELLows FALLS, VERMONT, ASSIGNOR TO IMPROVED PAPER MACHINERY COMPANY, OF CASTINE, MAINE, AND NASHUA, NEW HAMPSHIRE, A CORPORATION OF MAINE.

PAPER-MAKING MACHINERY.

SPECIFICATION forming part of Letters Patent No. 748,645, dated January 5, 1904.

Application filed June 7, 1901. Serial No. 63,506. (No model.)

To all whom it may concern:

Be it known that I, HOWARD PARKER, a citizen of the United States of America, and a resident of Bellows Falls, county of Windham, and State of Vermont, have invented certain new and useful Improvements in Paper-Making Machinery, of which the following is a specification, whereby any one skilled in the art may make and use the same.

10 Figure 1 is a side view of an embodiment of my invention. Fig. 2 is a side elevation in substantially a central vertical section of the same. Fig. 3 is a front elevation, partly in section. Figs. 4 and 5 are detail views 15 illustrating the manner of inserting new felt into the machine. Fig. 6 is a detail view showing the action of the upper roll when the paper-pulp is being taken from it. Figs. 20 7 and 8 are detail views, Fig. 7 showing the pulp on the roll and Fig. 8 the pulp as it is being stripped from the roll.

In the art of paper-making raw material or stuff is cut up into finely-divided particles and is generally mixed with a large quantity 25 of water, so that this pulp, which is very buoyant, is held in suspension in the water. It is collected into a sheet sometimes on the rolls, which revolve in the solution, and sometimes on the forming-screens or Fourdrinier wires. 30 It is often desirable to store or ship the pulp after it has been formed into a sheet and before it has been subjected to the final operations.

My invention has for its object to collect 35 the particles of pulp from the liquid in which it is suspended, to thoroughly dry it, and form it into compact sheets.

I have shown in the drawings and will herein describe a preferred form of embodiment 40 of my invention.

A A denote the columns of the machine, in which are located the bearings for the rolls.

B denotes the upper roll, on which the sheet of pulp is formed, carried in the bearings b b.

45 C C' denote the two lower rolls, which are carried in the bearings c c'. Adjacent to these rolls B C C' is located the tank D, containing the pulp in suspension. In this tank is revolvably mounted a suitable roll E for

collecting the pulp into a more or less compact sheet. The suction apparatus is connected with this roll to partially extract moisture and water from the pulp, as indicated by the arrows in Fig. 2. Adjacent to the part of the roll which is subjected to this suction action are located rolls d in adjustable bearings. Beyond these rolls d d d is located a second suction-roll F. An endless felt G passes over the idler g between the roll B and the rolls C C', over the idlers g' g² 60 g³ g⁴, between the rolls d and the suction-roll E, and around the suction-roll F. As the particles of pulp are collected into a sheet on the periphery of the roll E a considerable part of the moisture in the pulp is extracted 65 by the suction action on this roll. The small rolls d d d press the felt onto the pulp, and as the felt passes around the roll F it carries with it the pulp, and the opposite side of the sheet of pulp is subjected to the suction action of the roll F. The layer of pulp H (indicated by dotted lines in Fig. 2) is carried with the felt over the idler g and between the rolls B and C C'. The roll B is pressed into the rolls C C' by hydraulic 75 pressure exerted upon a piston in the cylinders I I and picks up the pulp carried by the felt. The empty felt passes about the roller C, idlers g' g² g³ g⁴, and again takes on a sheet of pulp as it passes between the first of 80 the rolls d and the suction-roll E. The sheet of pulp which is carried from the suction-roll on the felt to the roll B is quite thin and is collected in several layers on the roll B, where it is compacted by the pressure of this 85 roll on the rolls C C'. When a sufficient thickness of pulp is gathered on the roll B, the pulp is cut along the length of the roll, as indicated in Fig. 8, and the lower edge of the sheet is pulled away from the roll and 90 feeds out of the machine, as shown at K in Fig. 6. The felt meanwhile continues to deliver the thin sheet of pulp to the roll B, and as fast as a thick sheet is stripped from the roll a new sheet begins to be collected thereon. 95 It has been demonstrated by practice that if the bearings of the roll B are stationary the felt is subjected to a very great strain after

the end of the thick sheet of pulp has passed between the rolls B and C' and before it has passed from between the rolls B C and the felt is very quickly damaged or torn, so that it must be replaced. These felts are quite expensive, and the time consumed in replacing them occasions a considerable loss.

I have devised a means of permitting the roll B to swing or tip onto the roll C' after 10 the thick sheet of pulp has passed from between the rolls B and C' and the felt is thus relieved from the excessive strain to which it would be subjected between the roll B and the second roll C. In the drawings, b b' denote the bearings for the roll B. They are grooved to slide on the guides N N'. The bottom of the groove on the left-hand side normally bears against and slides on the guide N, while between the bottom of the groove 20 on the right-hand side and the guide N' there is left a clearance, as clearly shown in Fig. 1, to permit the bearings b b' to move to the right. A plate O is secured to the piston-rod of the piston in the cylinder I. Between this plate 25 and the top of the bearings are a series of rolls O' to permit of a free movement of the bearings b b' with respect to the plate O. The bearings and the plate are secured together by the straps m. By reference to Fig. 6 the action 30 of the roll B will be clearly understood. As soon as the end of the sheet of pulp K passes from between the rolls B C' the roll B is immediately thrown to the right and will occupy the position shown in Fig. 6. As soon as the 35 pulp K passes from between the rolls B and C the roll B will return to its normal position and the operation continue until the sheet of pulp on the roll B is again thick enough to be removed. I have also shown a means for 40 raising the rolls while the endless felt is being put into place. Connected with the cylinder I is the two-way valve P, opening into the top and bottom of the cylinder. When a new felt is to be put into the machine, I 45 first raise the upper roll B by admitting the steam, water, or other operating fluid to the the lower part of the cylinder I. Fig. 4 shows the rolls B thus raised, and G shows one side of the felt which is put in place between 50 the roll B and the rolls C C'. The roll B is now lowered into place, and the strap Q is placed over the axle of the roll B and under the axles of the rolls C C', as shown in Fig. 5. Water, steam, or other fluid is now ad- 55 mitted to the lower part of the cylinder under the piston, and all three of the rolls are raised, the driving-gears R R' on the rolls being disengaged from the driving-gear S. The bearing-boxes c c' for the rolls C C' are 60 now removed, and the other side of the endless felt may be put into place underneath the rolls C C', as is clearly indicated in Fig. 5. The boxes are then replaced and the rolls lowered into their bearings and the strap Q 65 removed. It is necessary to exert a considerable pressure on the roll B, and the above-described method of raising the roll B and

the rolls C C' for the purpose of introducing a new felt is a simple and easy way of doing it, by simply reversing the action of the pressure apparatus.

Fig. 7 shows the roll B with the thick sheet of pulp, and Fig. 8 shows this pulp after it has been cut lengthwise of the roll and one end stripped from the roll.

75

I claim as my improvement—

1. In a machine of the class specified, in combination the endless felt, a plurality of coacting rolls mounted in suitable bearings in the frame of the machine, one of said rolls being free to move to a limited extent from side to side with respect to the other rolls, substantially as described.

2. In a machine of the class specified, the combination with the frame and an endless 85 felt, of two or more rolls mounted side by side in suitable bearings in the frame, a roll coacting with the first two rolls and bearings for said roll, free to move to a limited extent from side to side.

90

3. The combination in a machine of the class specified with the frame and the two rolls mounted side by side in said frame, of a single roll coacting with the first two rolls, bearings for the single roll arranged to slide 95 vertically on guides and free to move to a limited extent from side to side.

4. The combination in a machine of the class specified with the frame, the two rolls mounted side by side in the lower part of the 100 frame, of a single roll coacting with the first-mentioned rolls, bearings for said rolls, a plate connected with the bearings for said roll, rolls located between said plate and said bearings, and means to move said plate vertically, substantially as described.

5. In a machine of the class specified the combination with the frame and the rolls supported in suitable bearings in said frame, of a pulp-tank arranged adjacent to said rolls, a 110 suction-roll mounted in said tank and adapted to form the pulp into a sheet on its periphery, and an endless pulp-carrying felt traveling over the roll mounted in the tank and adapted to pick off the sheet of pulp 115 therefrom, and a second suction-roll arranged adjacent to the first suction-roll and adapted to subject the opposite side of the sheet of pulp to the suction action.

6. In a paper-making machine, the tank, a 120 suction-roll revolvably mounted in said tank, a second suction-roll mounted adjacent to the first suction-roll, a forming screen or felt passing from one of said rolls to the other, said rolls being arranged to subject each side 125 of the felt and pulp carried thereby to the suction action, substantially as described.

7. In a machine of the class specified, the tank containing the solution, the suction-roll revolvably mounted therein, a second suction-roll mounted adjacent to the first-named roll, an endless felt passing over part of the periphery of the first roll and in the opposite direction about the other roll, and a series of 130

adjustable pressure-rolls arranged adjacent to and coacting with the first suction-roll, as and for the purposes specified.

8. In a machine of the class specified, the combination with the frame, of two or more rolls mounted side by side in suitable bearings in the frame, a roll coacting with the first two rolls, a felt passing over the two rolls and under the single roll, bearings for said last-named roll, a hydraulic cylinder arranged over each of the bearings of said roll, and the pistons in said cylinder connected with said bearings whereby a direct hydraulic pressure may be brought to bear on said roll, substantially as described.

9. The combination in a machine of the class specified with the frame and the rolls suitably mounted therein, of a hydraulic cylinder mounted over the bearings of one of the rolls, the piston in said cylinder, and connections between said piston and the bearings of one of said rolls, and a removable strap embracing the ends of the axles of each of the rolls, as and for the purposes specified.

10. In a wet-machine, a set of squeezing-rolls comprising a top roll and two under rolls, the latter being disposed in parallelism in the same horizontal plane, and the former located in a plane above the latter with its axis approximately midway between them, supports for said top roll movable back and forth whereby said top roll may move bodily relative to the under rolls, and means for vertically adjusting said supports.

11. In a wet-machine a set of rolls comprising a top roll and two under rolls, the latter being disposed in parallelism in the same horizontal plane, and the former located in a plane above the latter with its axis approximately midway between them, and supports for said top roll free to move back and forth, whereby said top roll may move bodily relative to the under rolls, substantially as described.

12. In a wet-machine, a set of squeezing-rolls comprising a top roll and two under rolls, the top roll being normally located above said under rolls, and supports for said top roll free to move to a limited extent from side to side, means for adjusting said supports vertically, a hydraulic cylinder and means for connecting said movable supports for the top roll therewith, substantially as described.

13. The combination in a machine of the class specified, with the frame, and two rolls mounted side by side in said frame, of a single roll coacting with the first two rolls, bearings for the single roll arranged to slide vertically on guides and free to move to a limited extent from side to side, a hydraulic cylinder, and means for connecting therewith said movable bearings for the single roll, substantially as described.

HOWARD PARKER.
